DESIGN FOR A DRESS ENSEMBLE

John F. Strassner, New York, N. Y.

Application December 20, 1948, Serial No. 150,254

Term of patent 3½ years

(Cl. D3—26)

To all whom it may concern:

Be it known that I, John F. Strassner, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is the front view of a dress ensemble, showing my design.

Fig. 2 is the rear view of the dress ensemble shown in Fig. 1.

Fig. 3 is a fragmentary front view of the dress member of the ensemble shown in Figs. 1 and 2, and

Fig. 4 is the fragmentary rear view thereof.

I claim:

The ornamental design for a dress ensemble, substantially as shown.

JOHN F. STRASSNER.
